UNITED STATES PATENT OFFICE.

FRANCIS J. PLYM, OF KANSAS CITY, MISSOURI.

STORE-FRONT CONSTRUCTION.

No. 846,843.

Specification of Letters Patent.

Patented March 5, 1907.

Application filed July 8, 1905. Serial No. 268,832.

To all whom it may concern:

Be it known that I, FRANCIS J. PLYM, a citizen of the United States, residing at Kansas City, in the county of Jackson and State of Missouri, have invented a new and useful Improvement in Store-Front Construction, of which the following is a specification.

My invention relates to store-front constructions, and more particularly to that portion supporting and surrounding the window-glass; and the objects of the invention are to provide a substantial frame in which the glass is adapted to rest, means for holding the glass rigidly as regards edgewise or lateral movement in one direction and yieldingly against lateral movement in the opposite direction to accommodate expansion and contraction of the glass, drainage for water from condensation on or which is used in washing the window-glass, and for a free circulation of air to prevent excessive condensation on the inside of the glass and the formation of frost thereon, it being well known that in the northern latitudes, where frost reigns for many months of the year, the merchants are put to much expense and trouble in keeping their show-windows free from frost.

With these objects in view the invention consists in certain novel and peculiar features of construction and organization, as herein-after described and claimed, and in order that it may be fully understood reference is to be had to the accompanying drawings, in which—

35 Figure 1 is a sectional perspective view of a store-front construction embodying my invention. Fig. 2 is a vertical section of the shelf portion of my improved store-front construction. Fig. 3 is a similar view of the 40 portion which presses the window-glass outwardly against the shelf and accommodates the expansion and contraction and variable thickness of the glass. Fig. 4 is a vertical section showing the store-front construction 45 in operative position with respect to the window-glass, the sill, and the floor of the window.

In the said drawings, 1 indicates the window-sill, and 2 the floor of the window. 3 indicates a metal plate fitting, by preference, against one edge of the floor and provided at suitable intervals with holes 4. 5 indicates a resilient gutter disposed at the opposite side of the upper portion of said plate from 55 the floor and, by preference, of integral for-

mation with the plate, and said gutter is provided at intervals with drain-holes 6.

A casing embodies a shelf-plate constructed as follows, and said plate is preferably formed by rolling, though that is immaterial, 60 the plate shown representing that which underlies the window-glass:

7 indicates the standard or upright portion, the same being arranged, by preference, parallel with plate 3.

8 indicates a gutter projecting inward from the lower edge of the standard and underlying gutter 5.

9 indicates the base portion underlying the gutter and standard, by preference, and resting upon and projecting to the outer edge of the sill 1.

10 indicates the shelf formed at the upper edge of the standard and provided at the edge or side most remote from plate 3 with 75 an upwardly-projecting flange 11, against which the window-glass 12, resting upon the shelf, is adapted to be held with a yielding pressure by the resilient gutter 5, as shown clearly in Fig. 4, it being understood, of course, 80 that the shelf may be of any suitable cross-sectional type which will serve to form a support for the window-glass and at the same time limit the outward movement of the latter.

85 By the arrangement described it will be apparent that water applied to the inner surface of the glass or produced thereon by condensation will flow into the gutter 5 and pass through the drain-holes 6 of the latter 90 into gutter 8 and escape through the drain-holes 13 in the lower portion of the standard.

It will also be noticed that should some of the water pass down between the glass and the gutter 5 it will be caught by the gutter 8, 95 and consequently be discharged through the drain-holes 13, and that should any water running down the outside of the glass pass under the latter and over the shelf it likewise will enter the gutter 8 and be discharged 100 therefrom through drain-holes 13.

The standard is provided at suitable points with apertures 14 in alignment with apertures 4, and through said aligned apertures wood-screws 15 or other fastening devices 105 extend and engage the floor of the window, so as to secure the standard at the proper point on the sill.

In securing the parts in position the standard is first disposed upon the sill a greater 110

distance from plate 3 than as shown in Fig. 4 in order that the window-glass may be placed upon the shelf without the necessity of repressing the resilient gutter. The screws or fastening devices 15 are then fitted in place and screwed home, so as to draw the standard and glass to the required position and cause the latter under the action of the spring-gutter to be pressed tightly against the flange of the shelf. As thus arranged it will be seen that the exit for the water is not only free and unobstructed, but that the drain-holes likewise provide for a free circulation of air around the glass and the consequent equalization of the temperature of both surfaces of the latter.

While the above description relates to that portion of the frame underlying and sustaining the weight of the window-glass, it is to be understood that similar perforated shelf portions are employed at the side and top edges of the glass in order that the air circulating through the various holes or apertures described may have access to the entire inner surface of the glass. It will likewise be understood that yielding means for applying outward pressure upon the glass near its side and upper edges will also be employed, and that if such means is in the form of a continuous gutter it will be perforated.

From the above description it will be apparent that I have produced a store-front construction possessing the desirable features of advantage enumerated in the statement of the object of the invention and which obviously may be modified in minor particulars without departing from the principle of construction involved.

Having thus described the invention, what I claim as new, and desire to secure by Letters Patent, is—

1. In a construction of the character described, the combination of a window-setting, a rigid shelf in the window-opening, formed with a portion projecting farther inward of said opening near one edge of the shelf than the other, a window-glass fitting edgewise against the face of the shelf, and a resilient means for applying lateral pressure on the glass to clamp it firmly against the said projecting portion of the shelf.

2. In a construction of the character described, the combination of a window-setting, a rigid shelf in the window-opening and provided with air-holes, and with a rigid portion projecting farther inward of said opening near one edge of the shelf than the other, a window-glass fitting edgewise against the face of the shelf, and resilient means for applying lateral pressure on the glass to clamp the same firmly against said projecting portion of the shelf.

3. In a construction of the character described, the combination of a window-sill, the floor of the window, a shelf supported

upon the sill, a window-glass resting upon the shelf, and a resilient gutter interposed between the floor and the lower portion of the window-glass and pressing the latter yieldingly against the shelf and away from the floor.

4. In a construction of the character described, the combination of a window-sill, the floor of the window, a shelf supported upon the sill, a window-glass resting upon the shelf, a resilient gutter interposed between the floor and the lower portion of the window-glass and pressing the latter yieldingly against the shelf and away from the floor, and fastening devices securing the shelf at the proper point upon the sill.

5. In a construction of the character described, the combination of a window-sill, the floor of the window, a shelf supported upon the sill, a window-glass resting upon the shelf, a resilient gutter interposed between the floor and the lower portion of the window-glass and pressing the latter yieldingly against the shelf and away from the floor, and screws extending through the shelf and into the floor of the window and securing said shelf at the desired point of adjustment.

6. In a construction of the character described, the combination of a shelf having one or more holes in its lower portion, a window-glass upon the shelf, and a resilient gutter pressing upon the lower portion of the glass to clamp it firmly upon the shelf.

7. In a construction of the character described, the combination of a shelf having one or more holes in its lower portion, a window-glass upon the shelf, and a resilient gutter pressing upon the lower portion of the glass to clamp the same firmly upon the shelf and provided with one or more drain-holes.

8. In a construction of the character described, the combination of a shelf, a gutter at one side of the shelf and adapted to discharge water externally of the latter, a window-glass upon the shelf, and means above the shelf applying a yielding pressure on the glass to clamp it firmly upon the shelf.

9. In a construction of the character described, the combination of a shelf, a gutter at one side of the shelf and adapted to discharge water externally of the latter, a window-glass upon the shelf, and a resilient gutter above the first-named gutter and provided with one or more drain-openings and applying a yielding pressure against the lower portion of the glass to clamp the same firmly upon the shelf.

10. In a construction of the character described, the combination of a window-setting, a shelf within and rigid with said setting and provided with one or more apertures, a window-glass within the window-opening and having edgewise engagement with the shelf, a flange at one edge of the shelf and overlapping the contiguous face of

the glass, and means for applying a yielding pressure laterally against the glass to press the same firmly against said flange.

11. In a construction of the character described, the combination of a window-glass, a rigid part engaging the same and preventing movement thereof edgewise or sideways in one direction and provided with one or more apertures, means applying a yielding pressure against the glass to clamp it firmly upon and laterally against said part and adjustable means for securing said part with the glass clamped between it and said yielding means.
12. In a window-front construction, a metallic plate comprising a standard, a shelf projecting substantially at right angles to the standard from one edge of the same and provided at its opposite edge from the standard

with a flange paralleling the standard, a gutter projecting from the opposite edge of the standard from the shelf, and in the opposite direction to the latter, and a base portion fitting against said gutter at the opposite side of the same from the shelf and projecting in the same direction but at a greater distance than said shelf from said standard.

13. In a construction of the character described a metallic plate having a resilient and substantially V-shaped gutter formed integrally with said plate and disposed at one side of the same and provided with drain-holes.
